FIG. 1.

INVENTOR.

INVENTOR.

UNITED STATES PATENT OFFICE

2,127,692

ENGINE

Marcus Lothrop, Berkeley, Calif.

Application September 30, 1935, Serial No. 42,754

7 Claims. (Cl. 123—79)

My invention relates to internal combustion engines and is especially concerned with a compression ignition engine of the single-valve type as disclosed in the copending application of Nathan C. Price et al., Serial No. 35,940, filed August 13, 1935, and entitled "Engine."

The patent literature discloses many different forms of internal combustion engines in which a single valve, usually a poppet valve, controls communication between the combustion chamber and the intake and exhaust ducts, and likewise shows various arrangements for controlling flow through such ducts. The present engine contemplates the use of a single poppet valve at the combustion chamber itself, arranged in series with a reciprocable distributor for controlling flow through the intake and exhaust ducts.

It is an object of my invention to provide such an arrangement in which lubrication is not needed.

Another object of my invention is to provide such an engine in which the arrangement is very like standard practice.

Another object of my invention is to provide such an engine in which the ingoing and outgoing flow is conducive to a high volumetric efficiency.

A further object of my invention is to provide such an engine in which scavenging is thorough.

An additional object of my invention is to provide such an engine in which the ingoing flow and the outgoing flow can be definitely controlled.

The foregoing and other objects of the invention are attained in the embodiment illustrated in the drawing, in which

Fig. 1 is a cross-section showing semi-diagrammatically in perspective a portion of the head of an engine constructed in accordance with my invention.

Fig. 2 is a diagram showing the events of the operating cycle.

In its preferred form the engine of my invention includes a single poppet valve at the combustion chamber in series with a distributor which is a reciprocating, valve-like member out of contact with its surrounding body and movable between a plurality of positions to assist in controlling the influx and the efflux of working fluid. The engine also preferably contemplates the use of means for establishing a positive flow of working fluid through the inlet and exhaust ducts.

As shown by the typical example illustrated in the drawing, the engine of my invention in its major aspects is conventional and incorporates a cylinder block 6 in which there is a cylinder bore

7 encompassed by a cooling water jacket 8. A piston 9 is adapted to reciprocate in the cylinder between a lower position and an upper position in which it forms the boundary of a combustion chamber 11. The combustion chamber is also partially bounded by a cylinder head 12, incorporating a cooling water jacket 13, and formed to provide a conical seat 14 for a poppet valve 16. This valve, in the customary fashion, has a relatively flat head 17 and a rod-like stem 18. The valve is guided by a bushing 19 pressed into the head 12 and is preferably urged towards closed position by a coil spring 21 interposed between the cylinder head 12 and a washer 22 detachably secured to the valve stem 18. A rocker arm 23, pivoted on a lay shaft 24, contacts the upper end of the valve stem 18 and is subject to the action of a cam 26 rotatably driven in time with the operation of the engine by a cam shaft 27.

The valve 16 controls flow between the combustion chamber 11 and a pair of passages 31 and 32 which together form a conduit merging with the combustion chamber at the seat 14 but which are separated by an intervening wall 33 or septum in general bisecting the space to provide two similar passageways. These turn to merge through openings 34 and 36 with a cylindrical bore 37 in the cylinder head 12. This bore at its upper portion merges with a passage 38 emerging from the side of the cylinder head 12 and connected to any suitable type of air blower 39 preferably driven by the engine, while at its lower end the bore 37 preferably merges with a passage 41 likewise emerging from the side of the head 12 and connected by a suitable pipe 42 to exhaust.

In order that flow in the intake passage 38 and the exhaust passage 41 can be properly controlled in conjunction with the general operation of the engine, I preferably provide a distributor 46 to operate in the cylindrical bore 37. This distributor is in general like a poppet valve and is provided with a head 47 which is preferably a very light, circular disc and a stem 48 merging with such disc. The stem is reciprocably mounted in a bushing 51 pressed into a cage 52 mounted in the cylinder head 12. The stem 48 is normally urged into an uppermost position by a coil spring 53 which encompasses the stem and rests with one end against the cage 52 and with the other end against a washer 54 removably secured to the valve stem 48. A rocker arm 56 is at one end in contact with the terminus of the stem 48 and at the other end is pivotally mounted on the lay shaft 24. A suitable cam 57 is mounted on the

cam shaft 27 to operate the rocker 56 and the distributor 46.

The disc-like head 41 of the distributor is preferably of somewhat smaller diameter than the bore 37 in order to provide a clearance space 58 therebetween. This space is shown in exaggeration in the drawing but in practice is several thousandths of an inch, in order that there will be no actual contact between the distributor disc 41 and the walls of the bore 37 but so that the leakage past such distributor disc 41 is a minimum amount.

The operation of the mechanism is described especially in connection with Fig. 2 which shows the events of the cycle since the cams 26 and 57 in Fig. 1 are illustrated diagrammatically. It is assumed that the engine is in operation and that the blower 39 is inducing a current of air to flow into the passage 38 to leak around the disc of the distributor 47 and into the passages 34 and 36 wherein it leaks around the terminus of the dividing wall 33 or septum and flows first in contact with the head 17 of the valve and thence outwardly through the passage 41 to the exhaust. This slight current of air is sufficient to maintain the parts somewhat cooler than they ordinarily would run, and likewise clears any pockets of residual exhaust gas and tends to maintain flow from the inlet toward the exhaust.

If it is assumed that the piston 9 is adjacent top dead center ready for injection, then the injector 61 (of any standard type) introduces the charge of fuel into the combustion chamber 11. The piston 9 begins its downward power stroke, and the valve 16 and the distributor 46 remain in the positions shown in Fig. 1 until the piston has arrived within a few degrees of bottom dead center, at which time the cam 26 actuates the valve 16 so that the head 17 moves into the dotted line position 62 in Fig. 1 and permits the products of combustion to flow outwardly from the combustion chamber 11 around the valve 16, through the passages 31 and 32 on both sides of the dividing wall 33, and through the outlets 34 and 36 into the bore 37 wherein their upper progress into the intake duct 38 is blocked by the distributor disc 47 so that they flow through the passage 41 into the exhaust pipe 42. The full area of the passages 31 and 32, as well as of the passage 41, is thus available for quickly exhausting the products of combustion, particularly when they are under an initial, relatively high pressure.

The exhaust continues preferably several degrees past bottom dead center position of the piston, at which time the cam 57 moves the distributor 46 into an intermediate position 63 (Fig. 1) wherein the distributor pauses so that air under pressure from the blower 39 enters the passage 38, flows downwardly through the upper half 60 of the bore 37, then is diverted through the opening 34 (reversing the previous direction of flow therein), and enters through the passage 31 into one side of the combustion chamber 11. Flow still continues outwardly from the combustion chamber, through the passageway 32, and out the opening 36 and the exhaust passage 41. There is thus established a positive scavenging flow through the passage 31 to one side of the combustion chamber, across the top of the piston, and 70 then out from the other side of the combustion chamber through the passage 32 to exhaust. This scavenging operation is considered important in the cycle of operation of the engine and is continued for a considerable period. The scavenging air is relatively low in temperature and not only

assists in cooling the moving parts but likewise reduces sensibly the temperature of the combustion chamber itself, so that upon a subsequent cycle the volumetric efficiency is somewhat increased due to the initially lower temperature. 5

The scavenging operation preferably continues until the piston 9 has again attained and passed top dead center position, at about which time the cam 57 causes further downward movement of the distributor 46 until the disc 47 assumes the dotted line position 64 in Fig. 1. In this position of the distributor disc there is no longer permitted communication between either the passage 31 or the passage 32 and the exhaust passage 41 (except possibly due to leakage), but the intake 15 passage 38 is in communication through both of the openings 34 and 36 with the passages 31 and 32 so that fresh air is positively forced into the combustion chamber 11 through both of the passages 31 and 32, and the entire area of the valve 16 is 20 useful for induction. Flow into the cylinder is assisted by the downward movement of the piston 9, but considerable supercharging can be effected since the clearance 58 around the distributor disc is relatively small and the loss of high-pressure 25 air directly into the exhaust line 41 around the distributor disc is insignificant.

The introduction of air continues until the piston 9 has again approximated bottom dead center position, at which time the cam 26 is effective to 30 permit the spring 21 again to position the valve 16 with the head 17 in contact with the valve seat 14. The combustion chamber 11 is then isolated from the passages 31 and 32. Shortly after the piston passes bottom dead center position and 35 begins the compression stroke, the cam 57 releases the rocker 56 so that the spring 53 is effective relatively quickly to move the disc 47 from its dotted line position 64 to the full line position in Fig. 1. Since this return movement of the distributor 46 is relatively rapid, there is a minimum loss of air from the inlet passage 38 into the exhaust passage 41. The parts have then all returned to their original positions and the cycle is repeated indefinitely during the operation of 45 the engine.

If thorough scavenging is unimportant, the distributor can be moved between exhaust position and inlet position directly without any intermediate pause at scavenging position. In this 50 event the dividing wall 33 or septum can likewise be omitted.

I claim:

1. An engine comprising means forming a combustion chamber, means forming a cylindrical bore, an inlet duct communicating with one end of said bore, an exhaust duct communicating with the other end of said bore, a pair of passageways separately communicating with said bore and jointly communicating with said combustion chamber, a valve for controlling communication between said passageways and said combustion chamber, a distributor reciprocable in said bore for controlling communication between said passageways and said inlet duct and said exhaust duct, means operating in time with said engine for periodically positioning said distributor to afford separate communication between one of said ducts and one of said passageways, and means for enforcing air flow through said inlet duct and out said exhaust duct when said distributor is so positioned. 55

2. An engine comprising means forming a combustion chamber, an inlet duct, an exhaust duct, means forming a cylindrical bore communicat- 70

ing at opposite ends with said inlet duct and said exhaust duct, means establishing separate communication between axially spaced parts of said bore and said combustion chamber, a valve for controlling communication between said combustion chamber and said establishing means, a distributor reciprocable in said bore and movable into a position between said axially spaced parts of said bore for controlling separate communication through said establishing means between said inlet duct and said exhaust duct, and means for forcing air to flow first through said inlet duct and then through said exhaust duct when said distributor is in said position.

15 3. An engine comprising means forming a combustion chamber, a conduit having two separate passages merging with said combustion chamber, a poppet valve controlling flow between said conduit and said combustion chamber, an exhaust duct, an inlet duct, reciprocable means for selectively connecting both of the passages of said conduit to said exhaust duct or said inlet duct and for connecting one of said passages to said inlet duct and the other of said passages to said exhaust duct, and means for forcing an air flow through said inlet duct and then through said exhaust duct.

4. An engine comprising means forming a combustion chamber, a single conduit having separate passages merging with said combustion chamber, a reciprocable valve for controlling flow between said conduit and said combustion chamber, a plurality of ducts merging with said conduit, means for establishing periodically during the operation of said engine communication between each of the passages of said conduit and said ducts, and means for forcing an air flow when said communication is established from one of said ducts through one of said passages into said combustion chamber thence through the other of said passages and the other of said ducts.

45 5. An engine comprising means forming a combustion chamber, a single conduit having a plurality of passageways merging with said combustion chamber, a valve for controlling flow between said conduit and said combustion chamber,

a plurality of ducts merging with said conduit, reciprocable means effective periodically during operation of the engine for selectively blocking communication between individual ones of said ducts and individual ones of said passageways, 5 and means effective periodically during operation of the engine to establish air flow into said combustion chamber through one of said ducts and passageways and out from said combustion chamber through the other of said ducts and passageways.

6. An engine comprising means forming a combustion chamber, a single conduit merging with said combustion chamber and divided into two passageways, a poppet valve for controlling flow 15 between said conduit and said combustion chamber, an inlet duct merging with said conduit, means for forcing flow through said inlet duct, an exhaust duct merging with said conduit, and reciprocable means including a disc out of rubbing contact with the walls of said conduit and said ducts adapted when in one position periodically but not entirely to prevent communication between one of the passageways in said conduit and 20 said inlet duct and the other of the passageways in said conduit and said exhaust duct.

7. An engine comprising means forming a combustion chamber, means forming a bore, a conduit merging with said combustion chamber and 30 communicating with said bore, a septum extending between said combustion chamber and said bore and dividing said conduit into an inlet passageway and an exhaust passageway, means defining an exhaust passage communicating with 35 said bore, means defining an inlet passage communicating with said bore, a distributor reciprocable in said bore, means operating in time with said engine for moving said distributor to register with said septum, and means for establishing 40 an air flow into said inlet passageway through said combustion chamber and out said exhaust passageway when said distributor registers with said septum.

MARCUS LOTHROP. 45
